United States Patent Office

Des. 203,629
Patented Feb. 1, 1966

203,629

CAN

James E. Brock, Orlando, Fla., assignor to Reynolds
Metals Company, Richmond, Va., a corporation of
Delaware

Filed Jan. 31, 1964, Ser. No. 78,456

Term of patent 14 years

(Cl. D58—17)

FIG.1

FIG.2

FIG.5

FIG.4

FIG.3

FIG. 1 is a top perspective view of a can showing my new design;

FIG. 2 is a top plan view thereof;

FIG. 3 is an enlarged cross-sectional view thereof taken on line 3—3 of FIG. 2;

FIG. 4 is a side elevational view thereof; and

FIG. 5 is a bottom plan view thereof.

I claim:

The ornamental design for a can, as shown.
